ABSORPTION REFRIGERATION

Kurt V. Nesselmann, Berlin-Siemensstadt, Germany, assignor to The Hoover Company, North Canton, Ohio, a corporation of Ohio

Application May 25, 1933, Serial No. 672,744
In Germany February 13, 1932

3 Claims. (Cl. 62—119.5)

This invention relates to refrigerating apparatus and more particularly to systems of the type in which inert gas is employed as a pressure equalizing medium so that refrigeration may be produced although the total pressure in the system is substantially the same throughout but the partial pressure of the refrigerant differs in different parts so as to enable the refrigerant to evaporate and produce a cooling effect in one part at a lower temperature than that at which it is changed to a more dense phase in another part of the system.

This particular invention involves improvements in a system of the type in which an absorption liquid is circulated through a number of vessels, some of which have an inert gas therein and others of which do not, and some of which operate at higher temperature than others. An example of such a system is disclosed in the co-pending application of Donald G. Smellie, Serial No. 490,497 filed October 22, 1930 for "Absorption refrigeration".

An object of the present invention is to devise improved means and methods for carrying out the principle disclosed in the aforesaid Smellie application, and for effecting certain economies therein.

Another object of the invention is to provide a refrigerating system of the type referred to in which improved means is used for circulating the absorption liquid through the various vessels.

Other objects and advantages reside in certain novel features of the arrangement and construction of parts as will be apparent from the following description taken in connection with the accompanying drawing in which,

The single figure is a diagrammatic representation of an absorption refrigerating system constructed in accordance with the principles of the present invention.

Referring to the drawing in detail, reference character 1 designates a boiler of the usual construction, which may be heated by an electric cartridge heater to cause refrigerant gas to be driven off from an absorption liquid therein. The gas so expelled may pass upwardly through a conduit 3 provided with heat radiating fins 4 so as to cause the vertical section of the pipe 3 to act as a rectifier.

At the point 5 the gas conduit 3 joins the gas conduits 6 which extends downwardly and unites with the right hand leg of a U-shaped conduit 7, at about the mid-portion of the leg. Conduit 7 conveys absorption liquid from the absorber 8 to a coil 9 located in a heat exchange vessel 10. The

upward end of the coil 9 is connected by a conduit 11 with a reversely bent pipe 12 provided with heat radiating fins, the pipe 12 being in turn connected to a small gas separating chamber 13. Absorption of gas takes place in the right hand leg of the conduit 7 (above the point of connection of gas conduit 6), the coil 9, the conduit 11, the bent pipe 12 and possibly to some extent in the vessel 13. These elements are thus component parts of what may be called a resorber. 65 The U-shaped conduit 14 may convey absorption liquid from the vessel 13 into the evaporator 15, which is shown as provided with fins on the outside and with a number of baffles 16 on the inside thereof, the latter acting to retain a portion of 70 the absorption liquid therein. A conduit 17 is provided to convey absorption solution from the bottom of the evaporator into heat exchange relation with a portion of the conduit 14 as illustrated, and into the heat exchange vessel 10. 75

Inasmuch as the liquid supplied to the vessel 10 by the conduit 17 is heated by the coil 9 in that vessel, some gas will be expelled therefrom which will pass off through the conduit 18 and join that gas coming from the boiler through 80 the conduit 3 as the junction point 5, this gas then flowing downwardly through the conduit 6 into the pipe 7 and upwardly through the coil 9.

The boiler 1 has a number of conduits connected thereto in addition to the gas conduit 3. A liquid conduit 19 connects the bottom of the boiler to the top of absorber 8, the portion of the conduit 19 adjacent the boiler being U-shaped and joining a small conduit 20 connected to the top of the boiler. As it leaves conduit 20 the conduit 95 19 passes downwardly, in heat exchange relation with the conduit 7, and upwardly to enter the top of the absorber 8. Liquid may thus flow from the boiler 1 to the top of the absorber 8 through the conduit 19. In the absorber, after trickling down over the baffle plates therein, the liquid collects in the lower portion of the absorber.

The absorber is connected to the evaporator by two large gas conduits 20 and 21, the conduit 20 being adapted to convey gas from the top of the absorber to the top of the evaporator, while the conduit 21 provides for the flow of gas from the evaporator to the lower portion of the absorber beneath the baffle plates thereof.

In addition to the baffle plates, the absorber is provided with a small cylindrical member 22 situated just below the entrance of the conduit 21 which causes the formation of a slight seal therein so that gas coming from the small gas separating chamber 13 through the conduit 23 may bubble 110

upwardly through the liquid collected around the cylinder 22, this seal preventing the flow of inert gas from the absorber into the gas separating chamber 13 through the conduit 23.

5 In addition to the aforesaid conduits the U-shaped conduit 24 connects the top of the heat exchange chamber 10 with the boiler 1.

The system may be charged with ammonia, water and hydrogen although it is apparent to 10 those skilled in the art that various other substances may be used without departing from the scope of the invention. Because this apparatus employs the resorber principle, the solution concentration will naturally be considerably lower 15 than that of apparatus employing a condenser, as is well known to those skilled in the art. Assuming the apparatus to be charged with the substances indicated above, and that heat is applied to the boiler 1 through the heating device 2, refrigerant gas will pass through the conduits 3 and 20 6 and circulation of absorption solution will take place as follows:

From the right hand leg of the conduit 7 where the conduit 6 joins the same, absorption liquid 25 will be lifted due to the gas bubbles therein from the conduit 6, up through the coil 9, conduit 11, cooling device 12 and into the vessel 13 from which it will flow through the conduit 14 into the evaporator. From the evaporator the absorption 30 liquid will flow through the conduit 17 into the heat exchange vessel and thence through the conduit 24 into the boiler. After being heated in the boiler, the liquid will flow through the conduit 19 into the top of the absorber, and after trickling 35 downwardly over the baffles and spilling over the top of the cylinder 22 at the bottom portion of the absorber, will pass through the conduit 7 back to the point where the conduit 6 joins the conduit 7 thus completing the cycle. It is to be noted 40 that there is only one circuit of absorption liquid, although there are four different concentrations in four different parts of this circuit, refrigerant being added to the absorption liquid in different degrees at 12 and 8 and removed therefrom at 1 and 15. Inasmuch as the refrigerant will evaporate from the solution in the evaporator into the inert gas and be absorbed from the inert gas in the absorber the inert gas will begin to circulate 45 under the influence of gravity in accordance with well-known principles.

Now, a basic feature of the single circuit type apparatus such as is here disclosed, is that the absorption liquid which flows through the evaporator, must be much stronger as it passes to 55 the evaporator than when supplied to the absorber for otherwise the refrigerant could not evaporate into the inert gas in the evaporator 15 at a lower temperature than that at which it is absorbed in the absorber 8 and no refrigerating 60 effect could be produced.

The apparatus shown on the right hand side of the drawing, that is the boiler 1, the vessel 10 with the coil 9 therein, the cooling device 12 and the small gas separating chamber 13, together 65 with the connecting conduits, provides means for weakening the absorption solution supplied to the absorber and for strengthening that supplied to the evaporator. These parts of the apparatus also provide means for causing the absorption liquid to circulate through its entire 70 circuit. The present invention provides a novel and ingenious way for accomplishing these results. The absorption liquid passing downwardly through the left hand leg of the conduit 17 connected to the evaporator is the coldest of any 75

portion of the absorption liquid during operation of the apparatus, this liquid coming directly from the evaporator. Compared to it, the liquid leaving the absorber in the conduit 7 is quite warm. Besides, the liquid in the conduit 7 is heated by heat exchange with the conduit 19 and by the addition of warm gas from the conduit 6, so that by the time it reaches the coil 9, it is quite warm. The absorption liquid in the coil 9 contains bubbles of gas which it is desired to have absorbed in the liquid, but absorption cannot readily take place if this coil is warm. By bringing this liquid into heat exchange relation in the vessel 10 with the cold absorption liquid coming from the evaporator through conduit 17, two objects are obtained. In the first place, it is possible to cause the absorption liquid in the conduit 7 and coil 9 to become very rich by picking up large amounts of refrigerant supplied to conduit 7 by the conduit 6, without the necessity of a large heat radiating surface, a comparatively small air-cooled coil, such as is indicated at 12 being sufficient for the purpose.

In addition to this, heat economy may be effected by pre-heating the absorption liquid passing from the evaporator through conduit 17 to the boiler and in this way a certain amount of refrigerant gas is expelled from the cold solution in the vessel 10 before this solution passes through the boiler, this expelled gas passing through the conduit 18 into the conduit 6.

A further advantage of the present arrangement results from the fact that by causing bubbles of gas entering the conduit 7 from the conduit 6 to displace a quantity of liquid therein, the absorption liquid is carried into the cooling device 12 which is located at the highest part of this system, so that the absorption liquid may flow by gravity from there throughout the remainder of its circuit.

It will be apparent to those skilled in the art that because of the employment of an inert gas in the evaporator and the absorber, (there being no inert gas in the remainder of the system) the refrigerant may be caused to evaporate and produce a cooling effect in the evaporator 15 as it evaporates from the strong solution supplied thereto and be conveyed by the inert gas into the absorber 8 to be absorbed by the very weak solution supplied thereto through the conduit 19. The solution strengthened somewhat in the absorber 8, may pass through the conduit 7, becoming mixed with more refrigerant gas as it does so and absorbing this gas as it flows through the coil 9, the conduit 11 and the cooling device 12, although these devices (referred to above as the resorber) are at the same or a higher temperature than the absorber 8. Any refrigerant not absorbed in the coil 9, pipe 11 and cooling device 12 may pass through the conduit 23 back to the absorber. To supply the refrigerant gas to strengthen this solution on its way from the absorber to the evaporator, the boiler 1 and vessel 10 are used, these devices at the same time weakening the solution passing to the absorber.

It is obvious that many changes may be made in the system and method without departing from the spirit of the invention or the scope of the annexed claims.

I claim:

1. In a refrigerating system of the continuous type the combination with a number of vessels comprising a boiler, an absorber, a resorber and an evaporator of means for circulating a liquid through all of said vessels in succession and in-

cluding a number of liquid conduits connecting said vessels in series, a portion of the resorber being in heat exchange relation with the conduit conveying liquid to the boiler, and means for conveying gas from the conduit conveying liquid to the boiler to the conduit conveying liquid to the resorber.

2. A refrigerating process comprising the steps of circulating an absorption liquid in a cycle between four vessels connected in series, said vessels constituting a boiler, an absorber, a resorber and an evaporator, causing the liquid to absorb refrigerant gas in the absorber and resorber, causing the refrigerant gas to be expelled from the liquid in the boiler and evaporator conveying the gas expelled in the boiler to the resorber, conveying the gas expelled in the evaporator to the absorber, bringing warm refrigerant laden liquid in a portion of the resorber into heat exchange relation with the colder refrigerant laden liquid passing to the boiler thereby causing the expulsion of some refrigerant gas from the liquid flowing to the boiler before it reaches the boiler and

conveying the refrigerant gas so expelled into contact with the liquid flowing to the resorber.

3. A refrigerating process comprising the steps of circulating an absorption liquid in a cycle between four devices connected in series, said devices constituting a boiler an absorber, a resorber and an evaporator, causing the liquid to absorb refrigerant gas in the absorber and resorber, causing the refrigerant gas to be expelled from the liquid in the boiler and evaporator, conveying the gas expelled in the evaporator to the absorber, bringing the warm refrigerant laden liquid passing through a portion of the resorber into heat exchange relation with the colder refrigerant laden liquid passing to the boiler thereby cooling the liquid flowing through the resorber and thus facilitating the absorption of refrigerant gas in the resorber, and thereby also causing the expulsion of some refrigerant gas from the liquid flowing to the boiler before it reaches the boiler, and conveying the refrigerant gas so expelled into contact with the liquid flowing to the resorber.
